(57) **CLAIM**

The ornamental design for a lid for containers, as shown and described.

DESCRIPTION

FIG. 1 is a perspective view of a lid for containers;
FIG. 2 is a front view thereof;
FIG. 3 is a rear view thereof;
FIG. 4 is a right side view thereof;
FIG. 5 is a left side view thereof;
FIG. 6 is a top plan view thereof;
FIG. 7 is a bottom view thereof.
FIG. 8 is a perspective view of a second embodiment of a lid for containers;
FIG. 9 is a front view thereof;
FIG. 10 is a rear view thereof;
FIG. 11 is a right side view thereof;
FIG. 12 is a left side view thereof;
FIG. 13 is a top plan view thereof; and,
FIG. 14 is a bottom view thereof.
The broken lines of the lid for containers is for the purpose of illustrating portions of the article and form no part of the claimed design.

1 Claim, 14 Drawing Sheets
